UNITED STATES PATENT OFFICE

CLARENCE H. BURNETT, OF CROOTHERSVILLE, INDIANA

CIGAR AND CIGARETTE HOLDER

Application filed January 31, 1930. Serial No. 424,840.

This invention relates to holders for cigars, cigarettes or the like and has as its primary object the provision of a holder which will prevent the staining of the fingers or hand 5 from smoke or tobacco, maintain one hand free of the odor of smoke, and further wherein the holder is of very light, yet strong and durable construction and of such a size as when placed on one's finger or otherwise supported for retaining a cigarette will prove 10 of no inconvenience.

Other objects and advantages of the invention will become apparent during a study 15 of the following description, taken in connection with the accompanying drawing, wherein:

Figure 1 is a perspective view showing the application of the holder through the forefinger of a hand,

Figure 2 is a perspective view of the holder per se,

Figure 3 is a vertical sectional view taken through the holder,

Figure 4 is a plan view of the blank for 25 forming the holder.

With reference more in detail to the drawing, it will be seen that my improved holder comprises a split ring 5 preferably made of light sheet metal but which can be made of 30 any other suitable material, the ends of which are spaced and slightly curved as at 6 so as not to pinch the finger when the ring is slipped thereon.

Formed integrally with the ring 5 are a 35 pair of resilient clamping jaws 7-7, which clamping jaws 7-7 are bent up from the ring 5, each of which members 7 are bent into concavo-convex form to form a substantially split ring like resilient clamp for engaging a 40 cigarette, cigar or the like, the members 7-7 engaging the cigarette, cigar or the like at opposite sides.

The ring 5 adjacent each end thereof is 45 provided with relatively short oppositely extending lateral extensions 8-8 for supporting the holder in a substantially perpendicular position on a table or the like against tilting. Thus it will be seen that the holder having a cigarette clamped between the jaws 50 thereof may be supported in a substantially

vertical position on a table or like support and will so support the cigarette as to retain the lighted end thereof above and away from the table cloth or other covering so that the possibility of the lighted end of the cigarette 55 coming into contact with the cloth or covering is reduced to a minimum. Thus the danger of the cloth becoming ignited by the cigarette is avoided unless of course the holder should be knocked over. However the lateral 60 fingers 8 provide substantial means for normally retaining the holder against being so knocked over, other than by force being applied to the holder.

It is thought that from the foregoing description, taken in connection with the accompanying drawing a clear understanding of the construction, utility and advantages of a cigar or cigarette holder of this character 65 will be appreciated by those skilled in the art 70 without a more detail description.

Even though I have herein shown the preferred embodiment of my invention, it is to be understood that the same is susceptible to changes in size, shape, and materials used as 75 fall within the spirit of the invention as herein described, and the scope of the appended claims.

Having thus described my invention, what 80 I claim as new is:

1. As a new article of manufacture, a tobacco user's appliance comprising in combination a ring provided with opposed pairs of oppositely extending lateral ears for supporting the ring on a support substantially perpendicular to the support, and clamping jaws carried by the ring on a portion of the ring diametrically opposite to said ears.

2. As a new article of manufacture, a tobacco user's appliance comprising in combination, a split ring provided adjacent its ends with pairs of oppositely extending lateral ears for supporting the ring on a support substantially perpendicularly, and clamping jaws carried by the ring and disposed diametrically opposite to the split in the ring.

In testimony whereof I affix my signature.

CLARENCE H. BURNETT.
